ATTORNEY.

UNITED STATES PATENT OFFICE.

HENRY WILCOX, OF NEWARK, NEW JERSEY, ASSIGNOR TO FRANK BRABSON, OF NEWARK, NEW JERSEY.

WINDOW-CATCH.

1,202,941.

Specification of Letters Patent. Patented Oct. 31, 1916.

Application filed July 6, 1915. Serial No. 38,053.

To all whom it may concern:

Be it known that I, HENRY WILCOX, a citizen of the United States, and a resident of Newark, in the county of Essex and State of New Jersey, have invented certain new and useful Improvements in Window-Catches, of which the following is a specification.

The objects of this invention are to provide a window catch which will enable one or both of the sashes to be open part way and yet locked against further opening; to thus enable the window to be open for purposes of ventilation without danger of any one entering or being able to open the window for entering; to limit the extent to which the window can be thus opened by releasably connecting one of the sashes to the window frame; to provide a construction whereby such connection can be adjusted to permit opening to different extents; to limit opening of one sash by engagement with the other; to secure simplicity of construction and operation, and to obtain other advantages and results as may be brought out in the following description.

Referring to the accompanying drawing, in which like numerals of reference indicate the same parts throughout the several views, Figure 1 is a perspective view of a window to which my invention is applied. Fig. 2 is a vertical cross-sectional view on line A—A of Fig. 1 showing the catch in operative position, and Fig. 3 is a vertical central cross-section of the catch showing the same in idle position.

In the specific embodiment of the invention illustrated in said drawings, the reference numeral 1 indicates a window comprising the usual frame 2 and vertically sliding upper and lower sashes 3, 4 respectively. Upon the upper rail of the lower sash is secured a portion of my improved catch 5 comprising a base 6 adapted to seat upon the said upper rail of the sash and preferably having a web 7 projecting upwardly therefrom intermediate its side edges. At the opposite ends of said web and in the same plane therewith are upwardly extending fingers 8, 9 providing a recess 10 therebetween, see Fig. 3. In positioning the device upon the sash, the plane of the web and said fingers is transverse to the plane 55 of the window, and the finger 9 farther

from the upper sash slopes upwardly away from said sash for purposes hereinafter set forth. Pivoted with respect to the base, and preferably upon the other of said fingers or finger 8 nearer the upper sash, is a latch 60 11, preferably slotted as at 12 to take over the finger 8 and extend upon opposite sides thereof toward the first-mentioned finger 9. The pivot pin 13 of said latch is near its lower edge and the end of the latch next 65 the finger 9 forms therewith a wedge-shaped space when the latch is in normal position, as shown in Fig. 3, so that a member such as a chain link forced downward between said finger 9 and latch end will tilt the latch away from the finger. The end of the latch away from the finger 9 provides a nose 14 at its top adapted to engage under a stop 15 on the side rail 16 of the upper sash 3 when the latch is swung as just described. In normal position of the latch, however, the stop 15 will pass the said nose 14 without engaging the same, and in order to retain the latch in this position unless 70 positively swung, a spring is suitably positioned for the purpose. As shown in the drawings, the lower edge of the nose end of the latch is recessed upwardly, as at 17, and the base plate 6 is recessed in registration therewith, as at 18, and within said 75 recesses is mounted a spring 19, but obviously the spring may be mounted or positioned otherwise if so desired, so long as it performs the function of swinging the latch to retain the nose 14 out of the path 80 of the stop 15.

Upon the window frame at the side of the window adjacent the latch 11 is secured a suitable chain 20, and preferably the same is placed substantially midway of the height 95 of the window. As shown, a plate 21 having a pair of outwardly projecting ears 22 at its opposite sides and a cross pin 23 between the ears is provided to carry the chain, the plate being screwed to the side of the window 100 frame and a link of the chain taking over the pin.

In operation, any one of the links may be hooked over the finger 9, and forced or wedged between said finger and the latch 11 105 so as to swing the latch toward the outer or upper sash 3. The lower sash may then be raised until the chain 20 is taut and obviously the chain must be short enough and properly positioned so as not to allow the 110

window to be opened far enough for a person to enter. With the latch swung outward by the chain link, the upper sash is limited in the amount it may be lowered by engagement of the stop 15 with the latch, and it is to be understood that the stop is low enough upon the sash to keep the window from being opened so far that a person might reach in and remove the chain. As shown 10 in the drawings, the various parts are arranged so that both the upper and lower sashes may be opened at the same time, but obviously it is within the scope of the invention to lower the stop so that with the lower 15 sash raised to the full extent allowed by the chain, the upper sash would have to be closed.

For greater strength and guidance of the latch 11 from tilting, I prefer to form upon 20 the base 6 lugs 24, 24 at opposite sides of the spring seat or recess 18 therein, and between which the latch enters as its nose-end swings downward.

Obviously detail modifications and changes 25 may be made in manufacturing my improved window catch without departing from the spirit and scope of the invention, and I do not wish to be understood as limiting myself except as required by the following 30 claims when construed in the light of the prior art.

Having thus described the invention, what I claim is:—

1. In a window catch, the combination of 35 a base adapted to be secured on one sash, a

latch pivoted with respect to said base and adapted to swing into position to limit by one end of itself movement of the other sash, a shoulder on said base adjacent the other end of said latch and forming therewith a wedge-shaped space, and means for introduction into said space to hold the latch tilted to limit movement of the other sash. 40

2. In a window catch, the combination of a base adapted to be secured on one sash, a 45 latch pivoted with respect to said base and adapted to swing into position to limit by one end of itself movement of the other sash, a shoulder on said base adjacent the other end of said latch and forming therewith a wedge-shaped space, and means attached to a fixed portion of the window and comprising a longitudinal series of members any one of which may be forced into said space to hold the latch tilted to limit movement of the other sash. 50

3. In a window catch, the combination of a base adapted to be secured on one sash, a latch pivoted with respect to said base and adapted to swing into position to limit by 55 one end of itself movement of the other sash, a shoulder on said base adjacent the other end of said latch and forming therewith a wedge-shaped space, and a chain adapted to be secured to a fixed portion of the window 60 and comprising links any one of which may be forced into said space to hold the latch tilted to limit movement of the other sash. 65

HENRY WILCOX.
